UNITED STATES PATENT OFFICE.

HOMER C. LA BATT, OF CHICAGO, ILLINOIS, ASSIGNOR TO WILLIAM J. HERRICK.

SHEET-FEEDING MACHINE.

1,092,272.

Specification of Letters Patent.

Patented Apr. 7, 1914.

Application filed December 18, 1903, Serial No. 185,624. Renewed January 10, 1910. Serial No. 537,337.

To all whom it may concern:

Be it known that I, HOMER C. LA BATT, a citizen of the United States, residing at Chicago, in the county of Cook and State of Illinois, have invented certain new and useful Improvements in Sheet-Feeding Machines, of which the following is a specification.

This invention relates to improvements in machines designed to feed sheets of paper successively from a suitably supported pile or stack to printing, ruling, folding and similar machines.

One of the objects of the invention is to generally improve the structure of such machines, particularly with reference to the means for holding the pile during the feeding off or delivery of the top sheet and also upon the withdrawal of the top sheet by the bucklers which operate upon the rear or side edges of the sheet to raise the same for the initial separation.

A further object of the invention is to so support or mount the holding means and bucklers that they may be adjusted independently of each other in order to secure uniform efficiency in the machine irrespective of variations in the thickness or flexibility of the paper.

The invention consists of the combinations and arrangements of parts hereinafter particularly described and designated in the appended claims, and it is illustrated in the accompanying drawings, in which—

Figure 1 is a sectional elevation of a sheet feeding machine, substantially on the line $x-x$ of Fig. 2 and showing the feeding off rolls, front feeding mechanism, one of the rear bucklers and one of the holding devices of my invention associated therewith;

Fig. 2 is a plan of the rear end of the machine shown in Fig. 1 and showing particularly the holding devices and the rear bucklers and the means for communicating motion thereto; Fig. 3 is a section on an enlarged scale on the line $y-y$ of Fig. 2, illustrating the holding device in its normal position and after the top sheet has been buckled and withdrawn from under the same; Fig.

4 is a view similar to Fig. 3 but showing the holding device in its elevated position to relieve the pressure on the pile and permit of the buckling of the top sheet; Fig. 5 is a detail front elevation of the holding

device, looking in the direction of the arrow Fig. 6; Fig. 6 is a plan view of the holding

device; and Fig. 7 is a detail side elevation of the presser foot.

In the operation of machines of the type to which the present invention relates, the initial separation of the top sheet from the pile or stack is effected at the rear, and in illustrating in the present instance one embodiment of the invention I have shown in the drawings only such parts as are necessary to show the operation of the machine so far as the separation and delivery of the paper are concerned. Such means comprise suitable bucklers acting on the rear of the top sheet, devices for holding the pile after the initial separation of the top sheet and during the delivery of the sheet and feeding devices for delivering the paper to the feeding off rolls which are located at the front of the machine and serve to eject the sheet from the machine and deliver it to the associated printing press, binder, or folder, etc.

The invention is concerned especially with the holding devices which are associated with the bucklers. These devices will be particularly described and the novelty clearly pointed out, while only such general description of the associated parts will be given as may be necessary to disclose the operation of the machine and the coöperation of the novel elements.

The stack or pile of sheets S to be fed to the printing press, folder or other machine is carried by a table T, which is designed to maintain the top sheet of the pile in such position as to be operated upon by the buckling and feeding devices, and may be automatically adjusted by any suitable mechanism adapted to attain this result. The table T is carried by a suitable supporting frame A, which forms the base or support upon which the various operative parts or elements of the machine are mounted. The frame is provided at its front end with suitable journal boxes in which is mounted a shaft S', and this shaft may be driven by any suitable mechanism. In the practical operation of the machine I prefer to take the power to drive the shaft S' by a connection from the press, folder or other machine with which the feeder is associated, although this is not material. The shaft S' is provided with disks s^{14} which are adapted to coöperate with disks s^{15} , fixed on a shaft s^{16} suitably journaled on the frame, to feed off the sheet or eject it from the feeder to the associated machine after it has been preliminarily sep-

rated from the pile, as hereinafter described. This mechanism may also be of any suitable character and operated in any preferred manner. The mechanism for delivering the 5 sheets to the feeding off mechanism may also be of any desired character. In the construction illustrated, the feeding devices B' employed for this purpose are supported by stubs or guide rods a extending from the 10 bearings in which the shaft S' is journaled and parallel with the sides of the table. Only one of the feeding devices is shown, although it is to be understood that a plurality are preferably employed and located 15 at suitable points along the width of the machine.

The feeding devices are actuated by operating connections located at opposite sides of the machine and one of such connections 20 is shown in Fig. 1. The connections referred to in this respect being similar, a description of one will serve for both. Reciprocating on the guide rod a at each side of the machine is a sleeve a² which is provided with an 25 upright or standard a³, upon which is slidably mounted a block a⁴ held in its lower position by means of a coil spring a⁵ interposed between the block a⁴ and a washer a⁶ on the end of the upright. The block a⁴ supports 30 one end of a rod a⁷ upon which the heads B are adjustably carried. The sleeve a² is reciprocated longitudinally and on its guide rod a by means of a link a⁸ which is pivotally attached at one end to an ear a⁹ on 35 the sleeve and at its opposite end to a disk a¹⁰ on the adjacent end of a shaft S² which is mounted in any suitable manner on the frame and operated by any preferred means as by a connection with the shaft S'. The 40 block a⁴ is raised on its upright against the spring a⁵ by an arm a¹¹, which is pivoted at a¹² to a riser a' secured on the frame at the rear of the disk a¹⁰, and freely engages the block at its front end. The arm a¹¹ is provided 45 with an antifriction roller a¹³ which is in the path of a cam portion a¹⁴ of the disk a¹⁰ to lift the parts against the stress of the spring a⁵.

In the operation of the front feeding devices just described through the medium of the mechanism at the opposite sides of the machine the feeders have imparted thereto a vertical and a horizontal movement. These 50 movements are so timed that as the sheet is buckled at the rear the feeders are drawn rearward and then lowered into engagement with the top sheet. The feeders are next moved forward carrying the sheet with them to the feed off mechanism and are then elevated out of engagement with the sheet.

A pair of guide rods A', one on each side of the machine, extends rearwardly from the risers a' heretofore mentioned. These 55 guide rods form the support for an adjustable carriage which carries the rear bucklers

and the holding devices associated therewith. The carriage comprises the opposite or end sleeves c mounted on, and adapted to slide longitudinally with reference to the guide rods A', and the pair of cross rods or 70 shafts c² and c³ which are mounted at their ends in the sleeves c. The sleeves c are locked against movement on the guide rods A' by means of set screws c'. The front shaft c² is adapted to rotate in its bearings, as 75 hereinafter described, but the rear shaft or rod c³ is fixed against movement. The adjustability of the carriage upon the guides A' permits the devices carried thereby to be set at any desired point over the longitudinal 80 area of the paper table, thereby adapting the machine to operate upon sheets of different sizes.

At one side of the machine is a longitudinal shaft S³, the rear end of which is shown in Fig. 2. This shaft may be journaled in any suitable manner and have motion communicated thereto through the medium of a connection with a driven part of the machine, as the main drive shaft S', or from 85 any other suitable source. The rear end of the shaft S³ extends approximately to the rear of the machine, and is provided with a key way or groove s³ as shown in Fig. 2. The shaft c² is rotated from the shaft S³. 90 To this end the latter is provided with a spiral gear s⁹, which engages and drives a corresponding gear c⁴ on a sleeve c⁵ loose on the shaft c³ and shown in dotted lines in Fig. 2. The gear s⁹ is provided with a feather or 95 spline to engage the groove s³ of the shaft S³, and is moved along its shaft by means of the inwardly projecting portions c⁶ of the carriage when the latter is moved on the guides A'. Motion is communicated from 100 the sleeve c⁵ to the shaft c² by means of the elliptical spur gear c⁷ on the sleeve and loose on the shaft c², which engages a corresponding gear c⁸ fixed on the shaft c². By this means the rotation of the shaft c² is given a varying speed, the parts being so adjusted that the slow speed of the shaft shall occur 105 while the bucklers that are driven thereby are in engagement with the paper, and the accelerated speed shall occur while the bucklers are out of engagement with the paper.

The rear carriage supports a pair of bucklers or pick ups which are adapted to operate upon the rear or side edges of the sheet and raise the top sheet from the pile for the initial separation. These bucklers may be of any desired construction and adapted to operate in any preferred manner. In the present instance each buckler 115 illustrated comprises a carrier E which is in the shape of a block having lateral ears provided with openings for the cross shafts or rods c², c³, and adapted to slide longitudinally upon such shafts, being held at 120 125 130

any desired point of adjustment laterally and with reference to the width of the sheets by means of suitable set screws e adapted to bear against the stationary shaft or rod c^3 . Carried by the block E is a rotating or other preferred form of pad or pick up P , adapted to be operated through the medium of a connection (not shown) with the rod c^2 . Associated with the bucklers are holders F against which the sheet is buckled when the pads P are operated and which permit the inflowing currents of air, supplied in any suitable manner and as is common with such machines, to pass beneath the sheet and separate its entire surface from the next sheet. The holders F are carried on the shaft c^2 and are adjustably secured thereon so that they may be set to agree with the different adjustments of the bucklers. These holders F may be of any suitable construction.

The mechanism heretofore described forms the subject matter of my Patent No. 968,062, dated August 23, 1910, and reference is made to such patent for a more complete description of the details of construction and operation of the same. I do not, however, limit myself in the present instance to the particular devices shown and described for buckling, feeding and delivering the sheets, as my invention contemplates and includes any suitable devices that are adapted to accomplish the same results and which may be associated with the improved holding device or devices now to be described.

Mounted on and supported by the shafts or rods c^2 , c^3 , so as to be capable of independent adjustment and associated with each pick up or pad P , is a holding device H , which is adapted to press upon and hold the pile with sufficient force to prevent the pile from being crowded or pushed forward under the pressure of the feeding devices when the latter are acting to deliver the top sheet, but which is automatically actuated to decrease the pressure on the pile during the operation of the rear bucklers to permit of the withdrawal of the corner of the top sheet from under the holding device when the sheet is buckled.

The holding devices, one of which is illustrated in detail in Figs. 3 to 7, inclusive, comprise, generally, a carrier associated with each of the rear bucklers and adapted to be adjusted independently of such buckler, a presser foot normally engaging the pile and under sufficient pressure to prevent the movement of the pile as a whole when the top sheet is moved by the feeding devices, and means for decreasing the pressure to such a degree as to permit of the withdrawal of the corner of the top sheet from under the presser foot when the rear bucklers are acting. In the specific embodiment of the invention illustrated I employ

a pair of springs of differing power or tension, one of which exerts strong pressure on the presser foot to hold the latter firmly against the pile, and a spring of less power to hold the foot against the pile when the first mentioned spring is thrown out of action. These springs act in alternation on the presser foot to the end that the said foot is always under spring pressure and constantly engages the pile. 75

In carrying out the invention a carrier H' is employed and provided with openings h' to receive the rods or shafts c^2 , c^3 , on which the carrier H' is adapted to slide. A set screw h^2 bearing against the shaft c^3 80 holds the carrier against movement and in its adjusted position. Extending upwardly from the carrier is a sleeve h^3 adapted to receive and in which slides a rod h^4 fixed to an arm h^5 extending rearwardly from the support H^8 carrying the presser foot H^2 . The support H^3 , and consequently the presser foot, is maintained in a normally depressed position, so as to hold the foot firmly against the pile, by an expansion 85 spring h^6 , which encircles the rod h^4 and reacts between a collar h^7 on the rod and the bottom of the sleeve h^3 in the passage h^8 of which the rod h^4 is adapted to slide. The support may be elevated to relieve the foot 90 of the pressure of the spring h^6 by any suitable mechanism, as by means of a cam h^9 , fixed on the shaft c^2 and rotating in a bifurcation h^{24} (Fig. 6) of the carrier H' , and which is adapted to engage an offset on 95 the support H^3 . Preferably and in order to reduce friction the offset takes the form of an antifriction roller h^{10} disposed in the path of the cam when the latter is rotated, and journaled on a stud h^{11} fixed to the support. From the foregoing it will be understood that as the cam turns in the direction of the arrow, Fig. 3, the roller h^{10} is engaged thereby, thus elevating the support 100 and taking the stress of the spring h^6 from the foot H^2 and placing it on the cam. This action takes place when or just before the rear bucklers engage the top sheet to buckle the corner of the same. The top sheet having been withdrawn from under the presser 105 foot H^2 the cam passes out of engagement with the roller h^{10} , permitting the spring h^6 to expand and return the parts to their original positions, as shown in Fig. 3, so that the presser foot under the full stress of 110 the spring h^6 will bear upon the second and under sheets to hold the pile against forward movement during the action of the feeding devices on the top sheet. The presser foot, however, is so mounted and 115 governed that it remains constantly in engagement with the pile, although when the top sheet is being buckled the pressure thereon on the pile is sufficient only to prevent the corner of the second sheet from being 120 125 130

withdrawn with the top sheet when the latter is buckled, and is not sufficient to interfere with the buckling of the top sheet. With this object in view the presser foot is placed under the independent control or influence of a second spring h^{12} , the tension of which is greatly less than that of the spring h^6 .

The holding foot H^2 may be carried directly by the support H^3 , but for a purpose to be explained it is carried at the lower end of a stem h^{13} , the said stem being provided with ears h^{14} between which the foot is pivoted. The foot is provided at its front end with a flat toe H^4 , the under face of which is normally in the plane of the surface of the pile, as shown in Fig. 3. Extending from the foot and rearwardly of the pivot is an extension h^{15} to which is pivoted the lower end of a vertical stem h^{16} . This stem passes through an aperture in a lug h^{17} fixed to the stem h^{13} and is provided at its end with a shoulder h^{18} between which and the lug h^{17} reacts the spring h^{12} which takes the form of an expansion spring coiled about the stem h^{16} . The function of the spring h^{12} is to move the foot on its pivot and maintain the same in contact with the pile when the support H^3 is elevated. Preferably the stem h^{13} is screw threaded and the shoulder h^{18} takes the form of a thumb nut adapted to screw upon the stem to adjust the tension of the spring to vary the pressure of the foot on the pile.

In practice each foot H^2 engages the pile near one side edge thereof as shown in Fig. 2 and as also there shown, each foot H^2 is so mounted as to have the general inclination of the buckler with which it is associated, although this is not essential or particularly material. By reason of the independent adjustment of the holding devices with regard to the rear bucklers the parts may be so adjusted as to deliver sheets of varying flexibility and thickness with equal facility.

In the operation of the machine, assuming the carriage upon which the bucklers and holding devices are mounted to have been properly adjusted with reference to the longitudinal area of the machine and the holding devices and bucklers to have been adjusted in accordance with the width of the pile and the character of the sheets to be delivered or separated, motion from the shafts S^3 is communicated to the shaft c^2 thereby actuating the buckling devices. Just prior to the engagement of the top sheet by the bucklers each cam h^9 engages the anti-friction roller h^{10} of the associated holding device and elevates the support H^3 , lifting the feet H^2 to relieve the pressure of the heavier springs, h^6 , on the top sheet of the pile. The feet H^2 , however, under the stress of the lighter spring, h^{12} , are moved on their

pivots, lowering the front ends of the feet and maintaining the toes on the top sheet under reduced pressure, as shown in Fig. 4. While the feet are held under the tension of the springs h^{12} the bucklers act upon the corners of the top sheet and during this operation and while the air is being forced under the top sheet to separate its surface from the next sheet, the springs h^{12} act upon the feet to hold the latter pressed upon the pile so that only the corners of the top sheet are moved by the bucklers from under the presser feet. As soon as the corners of the sheet are withdrawn by the bucklers from under the feet H^2 , the cams pass from out of engagement with the rollers h^{10} of the supports, releasing the latter, which by the expansion of the springs h^6 are quickly returned to their original position with the feet in the position seen in Fig. 3. As soon as the parts are returned so that the full effect of the springs h^6 is thrown upon the presser feet the feeding devices B' are operated to move the sheet to the feeding off disks which eject the sheet from the machine.

Each foot is adapted to be adjusted vertically to regulate the position of the same with reference to the height of the pile of sheets so as to maintain uniform efficiency in the operation of the machine and this adjustment is accomplished without effecting the tension of the springs h^6 . Each support H^3 is therefore provided with a vertical sleeve h^{19} and the stem h^{13} of the associated holding device extends through the sleeve and is screw threaded so as to be engaged by an adjusting nut h^{20} . The nut h^{20} is seated in a bifurcation h^{21} in the support H^3 which intersects the passage in the sleeve h^{19} . By turning the nut h^{20} the stem h^{13} may be raised or lowered as desired. Lateral or angular movement of the stem, and consequently of the foot H^2 , is prevented by a screw h^{22} which passes through the sleeve h^{19} and enters a longitudinal groove in stem. By this means the stem may be adjusted vertically, but is held against rotation.

To arrest the feet when they have reached their normal positions, that is to say with the bottom of each toe in a horizontal plane, as shown in Fig. 3, each foot may be provided with a shoulder h^{23} adapted to engage the stem h^{13} when its support is lowered.

Having described my invention, what I claim is—

1. In combination with a sheet feeding machine provided with a paper table and front feeding devices, a carriage adjustable lengthwise of the table, of a rear buckling device and a holding device mounted on the carriage at the rear of the buckling device, the said devices being adjustable laterally with respect to and independently of each other.

2. In combination with a sheet feeding machine provided with a paper table and front feeding devices, a guide located at each side of the table, and a carriage adjustable on the guides and lengthwise with respect to the table, of buckling and holding devices adjustable independently of each other and mounted on the carriage adjacent to the corners of the stack of sheets.
- 10 3. In combination with a sheet feeding machine provided with a table, front feeding devices and a buckler, of a holding device comprising a normally depressed support under spring pressure, a presser foot carried by the support, means for elevating the support, and means to positively move the foot independently of the support when the latter is elevated.
- 20 4. In combination with a sheet feeding machine provided with a table, front feeding devices and a buckler, of a holding device comprising a normally depressed support under spring pressure, a pivoted presser foot carried by the support, means for elevating the support, and a spring to move the foot independently of the support and when the latter is elevated.
- 30 5. In combination with a sheet feeding machine provided with a table, front feeding devices, and buckling devices, of a holding device associated with each buckling device and comprising a normally depressed support under spring pressure, a pivoted presser foot carried by the support, means for elevating the support, and means to positively move the foot on its pivot when the support is elevated.
- 40 6. In combination with a sheet feeding machine provided with a table, front feeding devices, and buckling devices, of a holding device associated with each buckling device and comprising a normally depressed support under spring pressure, a presser foot carried by the support, means for elevating the support, a rod adjustable vertically on and carried by the support, a foot pivoted to the lower end of the rod and a spring for rocking the foot on its pivot when the support is elevated.
- 50 7. In combination with a sheet feeding machine and its associated buckling and feeding devices, of a support, a pivoted presser foot carried by the support, a spring for holding the support depressed, means for elevating the support, a spring for moving the foot on its pivot when the support is elevated, and means to adjust the tension of the latter spring.
- 60 8. In combination with a sheet feeding machine and its associated buckling and feeding devices, of a support, a pivoted presser foot carried by the support, a spring for holding the support depressed, a cam for elevating the support, and a spring of less power than the first mentioned spring for moving the foot on its pivot when the support is elevated.
9. In combination with a sheet feeding machine and its associated buckling and feeding devices, of a support, a spring for holding the support depressed, a rod adjustable on the support, a presser foot pivoted to the end of the rod, and a spring of less power than the first mentioned spring for moving the foot on its pivot when the support is elevated.
- 10 10. In combination with a sheet feeding machine and its associated buckling and feeding devices, a pair of transverse shafts one of which is rotatable, of a support provided with an offset, a carrier mounted on the shafts and adapted to carry and guide the support, a spring for holding the support depressed, a cam on the rotatable shaft to engage the offset and elevate the support, a pivoted presser foot carried by the support, and a spring to move the foot on its pivot when the support is elevated.
- 15 11. In combination with a sheet feeding machine and associated buckling and feeding devices, a pair of transverse shafts one of which is rotatable, a vertically movable support provided with an offset, a carrier mounted on the shafts and adapted to carry and guide the support, a spring for holding the support depressed, a cam on the rotatable shaft to engage the offset and elevate the support, a vertically adjustable rod mounted on the support, a foot carried by the rod, and a spring to move the foot on its pivot when the support is elevated.
- 20 12. In combination with a sheet feeding machine and its associated buckling and feeding devices, a transverse shaft provided with a cam, a carrier provided with a vertical aperture, a support, a stem fixed to the support and sliding in the aperture, an expansion spring reacting against the stem to depress the support, an offset on the support adapted to be engaged by the cam to elevate the support, a sleeve on the support, a screw threaded rod extending into the sleeve, a nut engaging the stem to adjust the same, a foot pivoted on the lower end of the stem and provided with a rearward extension, a stem pivoted to the extension, a lug on the stem having an aperture through which the latter stem passes, a shoulder on the said stem, and a spring reacting between the shoulder and the lug.
- 25 13. A holding device for paper feeding machines comprising a shaft, a support, a spring for holding the support depressed, a cam on the shaft to elevate the support, a pivoted presser foot carried by the support, and a spring for moving the foot on its pivot when the support is elevated.
- 30 14. A holding device for paper feeding machines comprising a shaft, a support having a vertical aperture and a recess intersect-
- 105 110 115 120 125 130

ing the aperture, a spring for holding the support normally depressed, a cam on the shaft to elevate the support, a screw threaded stem slideable in the aperture, a nut end 5 gaging the stem and seated in the recess, a foot pivoted to the lower end of the stem and having a stop shoulder normally engaging the stem, a rearward extension on the foot, a vertical stem pivoted to the extension, a lug on the rod having an aperture

through which the stem passes, a shoulder on the stem, and a spring on the stem reacting between the lug and shoulder.

In testimony whereof I affix my signature in presence of two witnesses.
